UNITED STATES PATENT OFFICE.

PHILIP KENNEDY AND BERT KENNEDY, OF GLOVERSVILLE, NEW YORK.

BASEBALL GLOVE.

Application filed July 3, 1925. Serial No. 41,363.

Our invention relates to improvements in baseball gloves of the class known as fielding gloves, and it consists in the combinations, constructions and arrangements herein described and claimed.

The present invention contemplates the provision of a glove which may be broadly defined as having all the beneficial features of construction and operation of the baseball glove that is disclosed in Letters Patent of the United States 1,490,174 granted to Philip Kennedy on April 15, 1924. The glove of the present invention differs from the glove of the aforesaid patent in certain details of construction and the glove of the present invention has advantages which will be hereinafter set out and which arise from the novel and distinguishing structural features of the glove that the present invention provides.

An object of the present invention is the provision of a fielder's glove having a novel flexible and automatically adjustable connection between the back portions of certain adjacent fingers of the glove and between the thumb and adjacent finger of the glove, the flexible connection being engaged directly with the fingers and the thumb of the glove adjacent to the outer ends of the latter and being adapted to function as a result of the impact of a ball striking the palm of the glove near the base of the thumb of the glove to draw the ends of the fingers and the end of the thumb toward one another, thus producing a relatively deep pocket in the palm of the glove at the base of the thumb for the reception of the ball and staying the respective fingers of the glove to one another and to the thumb of the glove so that the impact of a ball striking against the front of any one of the fingers of the glove will be resisted by the combined action of all the fingers of the glove and the thumb as well, whereby not only will the fingers of the hand of a wearer of the glove be supported against being bent backward and broken by the ball but the impact of the ball against the glove will tend to close the glove automatically upon the ball so that the ball will be held firmly in the glove.

A further object of the invention is the provision of a glove in which the usual seam between the thumb stall and the body of the glove at the portion of the base of the thumb which is next to the first finger of

the glove is eliminated, whereby the glove is relatively strong at the place where the greatest stress will take place in service and ripping of the seam at the base of the thumb as a result of impact of the ball thereagainst is precluded.

Other objects and advantages of the invention will be apparent from the following description, considered in conjunction with the accompanying drawings, in which

Figure 1 is a back view of the improved glove,

Figure 2 is a fragmentary front view of the thumb, forefinger and adjacent portion of the glove,

Figure 3 is a plan view of a blank which includes the front or palm portion of the cover of the glove together with integral other adjacent portions of the cover of the glove,

Figure 4 is a plan of the blank which mainly forms the cover of the thumb of the glove.

The improved glove has a body generally indicated at 1 which is provided with the finger stall portions 2, 3, 4 and 5 respectively and the thumb stall portion 6.

The thumb stall 6 is formed with a pair of spaced eyelets 7 in the back portion of the thumb stall adjacent to the outer end of the thumb stall and near the row of stitching 8 which joins the inner edges of the front and back sections of the cover of the thumb stall to each other. The respective eyelets 7 are spaced longitudinally of the thumb stall, one of said eyelets being nearer to the extremity of the thumb stall than the other eyelet. The upper eyelet 7 and pairs of aligned eyelets 9-9, 10-10, and 11-11 which are formed in the back portions of the finger stalls 5, 4 and 3 respectively adjacent to the outer ends of such finger stalls, all lie substantially along the arc of a circle struck by a radius of relatively great length. The lower eyelet 7 and pairs of aligned eyelets 12-12 and 13-13 which are formed in the back portion of the finger stalls 5 and 4 respectively, likewise lie in the arc of a circle struck by a radius of slightly less length than the first mentioned radius about the same center. The lace 14 is threaded through the eyelets 11-11, 10-10, 9-9, and the upper eyelet 7 in turn, and then downwardly within the cover of the thumb stall 6 and out of the lower eyelet 7, and finally through the aligned eyelets

12—12 and the aligned eyelets 13—13 in turn, the ends of the lace 14 being knotted as indicated at 15 and 16 respectively to produce stops at the ends of the lace for preventing accidental withdrawal of the end portions of the lace through the eyelets 11—11 and 13—13 respectively. It is to be noted particularly that the eyelets are formed in the back portions of the covers of the finger stalls and the thumb stall so that no projecting parts are provided on the back of the finger stalls and the thumb stall. The lace 14 is of sufficient length to permit the fingers and the thumb of the glove to be opened out or spread to lie substantially in the same plane, as when the hand of the wearer of the glove is open. However, the impact of a blow resulting from the ball striking the palm of the glove will tend to cause the ends of the fingers and the thumb to move forwardly and inwardly as a unit since motion will be transmitted between the adjacent fingers 5, 4 and 3 and between the finger 5 and the thumb 6 by the flexible lace 14. A relatively deep pocket thus will be formed by the closing of the glove when the ball strikes the palm of the glove and the ball is not likely to escape from this pocket. Moreover, the lace stays the fingers 5, 4 and 3 to one another and to the thumb so that these fingers and thumb portion of the glove give combined support to the fingers of the hand of a wearer and tend to prevent injury to the hand of the wearer as well as to assure close fitting of the fingers of the glove over the ball in the pocket at the front of the glove. Since the eyelets through which the lace passes are in the back portions of the fingers and thumb of the glove, the fingers 5, 4 and 3 will be firmly stayed to each other and to the thumb 6 and the transmission of motion between adjacent fingers which are connected by the lace or between the thumb and adjacent finger 5 will be immediate. One end portion of the lace is connected with the third finger of the glove and the other end portion of the lace is connected with the second finger of the glove, thus permitting desirable flexibility of the third and fourth fingers of the glove.

The cover of the glove includes a section shown in Figure 3 which comprises the palm portion 17, the front portions 18, 19, 20 and 21 of the covers of the finger stalls 5, 4, 3 and 2, respectively, together with a portion 22 which includes the outer portion of the back of the cover of the fourth finger 2 and extends downwardly at the back of the glove to provide a lateral marginal portion of the back of the cover of the glove as shown in Figure 1. The construction of the cover of the glove shown in Figure 3 also includes an integral laterally extending portion 23 which constitutes the opposite lateral marginal portion of the cover

of the back of the glove. An opening 24 is formed in the aforesaid section of the cover of the glove at the juncture of the palm portion 17 with the lateral marginal portion 23 of the back of the glove. The inner lateral edge of the opening 24 is convexly curved, thus producing a flap 25 on the palm portion of the cover of the glove. The opening 24 also is formed at the end thereof proximate to the front portion 18 of the first finger of the glove to produce a tongue 26 on the palm portion of the cover of the glove extending into the opening 24. The cover of the thumb of the glove is formed mainly in one piece as shown in Figure 4 and includes a front portion 27 and a back portion 28. The lower edge of the front portion of the thumb piece is attached by stitching to the edge of the flap 25 on the palm portion of the glove as indicated at 29 and to the edge of the palm portion of the glove at the lower end of the opening 24 as indicated at 30. The lateral edge portion of the front of the thumb piece is secured by stitching to one side edge of the tongue 26, as at 31. The side edge portion of the back 28 of the thumb piece is secured by stitching for part of its length to the other side edge portion of the tongue 26, as at 32 (see Fig. 2) while the remainder of the side edge portion of the back 28 of the thumb piece is secured by stitching to the adjacent edge of the portion 23 of the back of the cover of the glove, as indicated at 33 in Fig. 1. The meeting edges of the front and back portions of the thumb piece at the upper ends of said portions are secured together by the aforesaid stitching 8. It of course will be understood that the stitching referred to in the foregoing as connecting various edge portions of the thumb piece to adjacent edge portions of the cover of the glove may be provided in one continuous row. When the thumb piece 27—28 is attached to the cover of the body of the glove along the edge of the opening 24 in the manner just described, the tongue 26 will be secured to adjacent edge portions of the thumb piece in position to extend as a part of the cover of the glove above the base of the thumb at the juncture of the thumb with the body of the glove and at the place at the front of the glove at which the greatest stresses are imposed because of the impact of the ball striking the glove. In other words, the front portion of the cover of the body of the glove is continuous with the cover of the thumb of the glove at the inner side of the thumb of the glove for part of the length of the thumb and the line of stitching which connects the thumb piece to the body of the glove at the inner side of the thumb is located on the cover of the thumb of the glove outwardly beyond the place of

contact of a ball with the palm portion of the glove at the base of the thumb of the glove. The provision of the flap 25 also serves to locate the stitching between the 5 lower edge of the front side of the cover of the thumb and the adjacent portion of the cover of the body of the glove above the place on the palm of the glove at the base of the thumb which is likely to be 10 struck by a ball when the glove is in use. The impact of a ball against the side portion of the glove at the base of the thumb therefore is not likely to cause breaking of the threads of the seam between the front 15 piece and the cover of the body of the glove and moreover the portion of the cover of the glove between the thumb and the body of the glove at the inner side of the base of the thumb has greater pliability when 20 it is made of a given material, such as leather than would be possible were this portion of the cover of the glove formed in pieces connected by stitching as is usual and not in a single piece as is done in forming a glove according to the present invention.

The thumb stall 6 and the first finger 5 of course may be additionally connected by the flexible web or connecting strip 34. This 25 strip is located approximately midway between the juncture of the base of the thumb with the body of the glove and the portions of the lace 14 which extend between the outer end portions of the thumb and first finger 35 of the glove.

It also will be observed that the front portion of the cover of the glove is secured at the edge of its wrist portion to the lining of the glove by lacing, thus permitting re-packing 40 of the glove or adjustment of the packing of the glove as desired to produce a desirable pocket in the palm of the glove under the impact of a ball and also precluding objectionable stiffness at the edge of the wrist 45 portion of the glove.

Obviously, the invention is susceptible of embodiment in forms other than that which is illustrated in the accompanying drawings, and we therefore consider as our own all 50 such modifications and adaptations thereof

as fairly fall within the scope of the appended claims.

We claim:—

1. A glove having a body formed with a thumb and finger portions, said thumb having spaced openings in the back of a cover thereof adjacent to the inner side of the thumb and a plurality of said fingers having spaced openings in the back portions of the covers and at opposite sides of the longitudinal median lines thereof, and a flexible connecting member threaded through said openings in said fingers of the glove and in the thumb for adjustably connecting said fingers of the glove to one another and to said thumb. 55

2. A glove comprising a body having a thumb and finger portions, said thumb having a pair of openings in the cover portion thereof at the back and inner side of the thumb said openings being spaced longitudinally of the thumb and the upper of said openings being located adjacent to the extremity of the thumb, a pair of transversely aligned openings in the cover of each of the first, second and third fingers of the glove at the back of the glove adjacent to the extremity of that finger, a second pair of transversely aligned openings in the cover of each of the first and second fingers of 80 the glove below the first named pair of transversely aligned openings in the back of the same finger, and a lace threaded through the first named opening in the third, second and first fingers and the upper opening of the thumb in turn and then passed outwardly from the inner side of the cover of the thumb through the lower opening in the cover of the thumb and threaded through the second named opening in the first and second fingers of the glove, said 85 lace having stop means at the ends thereof for preventing withdrawal of said ends of the lace through the openings in the second and third fingers of the glove, respectively, 90 said openings in the fingers and in the thumb of the glove having eyelets mounted therein. 95
